CASSEROLE

Glenn B. Beckman, Corning, N.Y., assignor to Corning Glass Works, Corning, N.Y.

Filed Mar. 1, 1972, Ser. No. 231,059

Term of patent 14 years

Int. Cl. D7—02

U.S. Cl. D7—28

Fig. 1

Fig. 2

Fig. 3

Fig. 4

FIG. 1 is a top plan view of a casserole embodying my new design.

FIG. 2 is a side elevational view thereof, the side opposite being identical.

FIG. 3 is an enlarged fragmental sectional view taken along line 3-3 of FIG. 2.

FIG. 4 is an enlarged sectional view in elevation taken along line 4-4 of FIG. 2.

I claim:

The ornamental design for a casserole, as shown and described.
